UNITED STATES PATENT OFFICE.

JAMES T. GROTHUIS, OF ORANGE CITY, IOWA.

OIL BURNER.

Application filed May 13, 1926. Serial No. 108,823.

My invention relates to oil burners of the gravity feed type, and it is my object to provide such a burner which is of simple, durable and inexpensive construction.

More particularly, my invention has to do with that type of oil burners in which a mixing bowl, having a multi-perforated side for entrance of air, and having an imperforate bottom to retain a charge of liquid fuel, is supported below a central perforation in the top of a casing which surrounds the bottom, to provide an air flue.

It is my object to provide such a burner in which the top, together with the mixing bowl, may be readily removed from the casing to allow inspection, repair, cleaning and the like.

Another object is to provide such a burner in which the parts are arranged to allow a continuous air blanket to flow between the upper edge of the bowl and the edge of the aperture in the top, so as to prevent contact of the flame with the edge of said aperture.

A still further object is to provide an overflow construction which will not interfere with the removal of the bowl from the casing, and which will not collect carbon and the like resulting from the combustion within the burner.

With these and other objects in view, my invention consists in the construction, arrangement and combination of the various parts of my device, whereby the objects contemplated are attained, as hereinafter more fully set forth, pointed out in my claims and illustrated in the accompanying drawings, in which:

Fig. 1 is a plan view of the burner.

Fig. 2 is a plan view of the burner base with the top and bowl removed.

Fig. 3 is a sectional view taken on the line 3—3 of Fig. 1, and

Fig. 4 is a detail sectional view, taken as indicated by the line 4—4 of Fig. 3.

I am aware that it is not new in oil burner construction to use a perforated bowl suspended within an air casing, below an apertured top, in such a manner that the draft of air will pass upwardly through the casing and enter the bowl through the perforations and thence pass out through the aperture in the top.

In such a burner, however, as well as in most types of burners, certain problems are encountered, such as the tendency of the overflow pipe (which is an essential element

in gravity feed burners), to clog with carbon, soot and the like, the clogging and carbonizing of the bowl, and the carbonizing of the edge of the aperture from which the flame issues.

In the burner shown and described herein I have met these problems by certain features of construction which allow very ready disassembling of the burner for cleaning and inspection purposes, and other features which I will hereinafter more fully describe.

The air casing of the burner is preferably cylindrical in shape, and has a cylindrical side wall, 10, open at both ends, which may be formed satisfactorily of sheet metal. The base is formed of a cast metal ring, 11, having an upstanding flange, 12, which forms, together with the ring, 11, the shoulder, 13, to receive the lower edge of the side wall, 10.

The side wall is secured to the flange, 12, by any suitable means, such as the screws, 14.

The top of the casing is formed as a ring-shaped plate, 15, having a central aperture, 16, and a downwardly extending flange, 17, which fits within the side wall, 10, and properly positions the top relative to the casing.

The mixing bowl is of sheet metal construction and comprises the cylindrical side wall, 18, provided with a large number of small perforations, 19, and secured at its lower end to an imperforate bottom or oil pan, 20.

The pan, 20, is stamped out of a single sheet of metal to provide the upwardly extending flange, 21, and the gutter, 22. The flange, 21, is welded or otherwise suitably secured to the side wall, 18, and the gutter, 22, surrounds the bowl below the lowest row of perforations, 19. At one side a lip, 23, is formed in the gutter, 22, to discharge overflow oil.

The mixing bowl is supported from the top by means of brackets, 24, secured to the bowl, offset outwardly as at 25 and thence extending upwardly with the screw threaded portions, 26. The portions, 26, are received through openings (not shown) in the top, 15, and are provided with nuts, 27 and 28, above and below the top for securely positioning the bowl relative to the top and allowing adjustment of the spacing of the bowl for a purpose which will now be explained.

It will be noted that the diameter of the bowl is slightly larger than that of the aper-

ture, 16, so that the main volume of air passing upwardly through the air casing will enter the bowl through the apertures, 19. Oil which has been delivered to the bowl and 5 allowed to collect in the pan, 20, will be heated by conduction downwardly from the side walls, 18, and radiation, and will be converted into a vapor which will pass upwardly toward the aperture, 16. This vapor 10 will be intimately mixed by a multitude of fine jets of air passing into the bowl from the openings, 19, and which will burn with a column of flame extending upwardly from the burner.

15 It is well understood by engineers that a yellow flame is the most efficient for an oil burner in the production of heat, and I find that with the burner shown a substantially perfect combustion can be obtained. However, 20 the combustion in the aperture, 16, is not complete, and in oil burners of this type, it has been found that carbon will deposit upon the edge of the aperture, especially at the points where the brackets connect the 25 bowl with the top. Prevention of carbon deposit can be obtained by allowing a space of air between the upper edge of the bowl and the edge of the aperture. The two are so positioned that a continuous sheet of air 30 will entirely cover the surface of the aperture and prevent the flame touching it at any point. I find that by offsetting the brackets as shown, this stream of air, although it 35 divides around the brackets, will reunite before it strikes the aperture and will form a continuous blanket around the entire edge of the aperture.

As a result, the aperture is left perfectly bright and clean at all times during the operation of the burner. This is important inasmuch as carbon deposits upon the edge of the aperture will affect the flame issuing from the burner in such a way as to reduce its heating efficiency.

45 The oil delivery pipe comprises a section of piping, 28, threaded into a boss, 29, formed in the base of the burner and having at its upper end an elbow, 30, terminating closely adjacent the side wall of the bowl. 50 The elbow is connected with the bowl by means of a nipple, 31, extending through an opening, 32, in the side wall, 18, and threaded as at 33 into the elbow, 30. Thus oil is delivered to the pan, 20, without the possibility 55 of leaking outside the bowl, and yet, when it is desired to remove the bowl, the nipple, 31, may be simply reached through the aperture, 16, unthreaded from the elbow, 30, and withdrawn through the opening, 32. When 60 it is desired to adjust the spacing between the bowl and top, both of the nuts, 27 and 28, may be rotated.

Difficulty has been experienced with overflow pipes, when they are connected to the 65 bowl, becoming clogged with carbon. I

therefore provide an overflow pipe, 34, which communicates with a cup, 35, formed in the base. The cup, 35, is positioned directly below the lip, 23, so as to receive the overflow oil from the gutter, 22. Since there is no 70 direct connection with the interior of the bowl, there is no possibility of carbon entering the overflow pipe, and since there is no connection whatever with the bowl, the overflow does not interfere with the removal of 75 the bowl.

A further advantage in this construction lies in the fact that where the overflow is connected directly with the member in which combustion takes place, the heat which is 80 communicated to the pipe will carbonize the oil flowing through it. In my construction this is not possible.

Some changes may be made in the construction and arrangement of the parts of 85 my invention without departing from the real spirit and purpose of my invention, and it is my intention to cover by my claims any modified forms of structure or use of mechanical equivalents which may be reasonably included within their scope.

I claim as my invention:

1. In an oil burner, a casing having an open top, a centrally apertured cover plate loosely resting over said top, a mixing bowl suspended from said top and surrounding said opening, an oil delivery pipe secured in the base and terminating near the bowl, and a nipple extended through a wall of the bowl and having a detachable connection with the said pipe, said nipple being accessible through the aperture of the cover plate and removable into the bowl to allow removal of the top and cover plate from the casing. 95

2. In an oil burner, a casing having an open top, a centrally apertured cover plate loosely resting over said top, a mixing bowl suspended from said top and surrounding said opening, an oil delivery pipe secured in the base and terminating near the bowl, and a nipple extended through a wall of the bowl and having a screw threaded connection with said pipe, said nipple being accessible through the aperture of the cover plate and removable into the bowl to allow removal of the top and cover plate from the casing. 100

3. In an oil burner, a casing, a centrally apertured top on said casing, said top having 110 an edge surrounding the aperture, which is curved downwardly and outwardly, to form a curved edge surface merging with the under surface of the top, a mixing bowl of cylindrical shape having its upper extremity 115 completely open and its upper edge concentric with the top aperture and spaced below the top closely adjacent the termination of said curved edge surface, and brackets secured to the bowl, offset outwardly, and 120 125 130

- thence extended upwardly and secured to the top, thereby allowing the said air sheet to be reunited after passing the brackets, before reaching the edge of the aperture.
- 5 4. In an oil burner, a casing having an open top, a centrally apertured cover plate loosely resting over said top, a mixing bowl suspended from said top and surrounding said opening, said bowl having a multi-
10 perforated side wall and a gutter surrounding said wall below the lowermost perforations, said gutter having a discharge lip, and an overflow receiving cup in the casing below said lip.
- 15 5. In an oil burner, a casing having an open top, a centrally apertured cover plate loosely resting over said top, a mixing bowl suspended from said top and surrounding said opening, said bowl having a multi-
20 perforated side wall and a gutter surrounding said wall below the lowermost perforations, said gutter having a discharge lip, an overflow receiving cup in the casing below said lip, an oil delivery pipe secured in the
25 base and terminating near the bowl, and a nipple extended through a wall of the bowl and having a detachable connection with the said pipe, said nipple being accessible through the aperture of the cover plate and removable into the bowl to allow removal of 30 the top and cover plate from the casing.
6. In an oil burner, an air casing, a mixing bowl suspended from the top of said casing, said wall having a multi-perforated side wall and an imperforate lower portion over 35 which oil may overflow, a gutter secured to the exterior of said imperforate portion in position to receive overflow oil and adapted to direct such overflow oil to a particular position, and an overflow receiving cup 40 under said position, and removed from the zone of heat which will produce carbonization.
7. In an oil burner, a casing, a mixing bowl suspended within said casing, said mixing bowl having an imperforate lower portion over the upper extremity of which oil may overflow, a gutter surrounding said imperforate portion to receive said overflow oil, said gutter being arranged to discharge 45 oil at a particular position and an overflow receiving cup under said position and removed from the zone of heat which will produce carbonization.

Signed at Sioux City, in the county of Woodbury and State of Iowa, this 7th day of May, 1926.

JAMES T. GROTHUIS.
